United States Patent [19]

Meyer

[11] Patent Number: Des. 313,562

[45] Date of Patent: ** Jan. 8, 1991

[54] SLIDE CALIPER

[76] Inventor: Hans Meyer, 24, rue du Bugnon, 1020 Renens, Switzerland

[**] Term: 14 Years

[21] Appl. No.: 169,355

[22] Filed: Mar. 17, 1988

[30] Foreign Application Priority Data

Sep. 22, 1987 [CH] Switzerland 116,190

[52] U.S. Cl. D10/73

[58] Field of Search D10/70, 71, 72, 73, D10/74; 33/783, 784, 792, 793, 794, 795, 796, 797, 798, 799, 800, 801, 802, 803, 804, 805, 806, 807, 808, 809, 810, 811, 812, 813, 814, 815, 816, 817, 818, 819, 820, 821, 822, 823, 824, 825, 826, 827, 828, 829, 830, 831, 832
